UNITED STATES PATENT OFFICE.

CYRUS CHAMBERS, JR., AND S. BERNARD CHAMBERS, OF PHILADELPHIA, PENNSYLVANIA; SAID S. BERNARD CHAMBERS ASSIGNOR TO SAID CYRUS CHAMBERS, JR.

GLOSSING-MACHINE.

SPECIFICATION forming part of Letters Patent No. 247,745, dated October 4, 1881.

Application filed July 21, 1881. (No model.)

To all whom it may concern:

Be it known that we, CYRUS CHAMBERS, Jr., and S. BERNARD CHAMBERS, of Philadelphia, in the county of Philadelphia and State of Pennsylvania, have invented certain new and useful Improvements in Glossing-Machines; and we do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a perspective view of our improved machine. Fig. 2 is an end view. Fig. 3 is a side elevation. Fig. 4 is a plan view. Figs. 5, 6, 7, 8, and 9 are details on an enlarged scale.

The same letter indicates the same part wherever it occurs in the drawings.

Our improvements relate to a machine for sizing and varnishing paper, patented by Richard McNamee August 1, 1877, No. 194,453, and reissued to Allen, Lane, and Scott, as assignees of said McNamee, September 10, 1878, No. 8,407.

Our improvements consist, first, in substituting for the conveyer-tapes a broad apron which carries the sheet to be varnished; second, in devices for tripping the varnish-fountain at the will of the attendant, for purpose hereinafter stated; third, making the roller over which the apron runs serve as a main shaft from and by which power is communicated to the other parts of the machine; fourth, giving a positive motion to the apron by means of sprocket-wheels working into a safety-chain to which the edges of the apron are attached; fifth, hanging the swinging frame on journals concentric with the roller which carries the apron; sixth, preventing the apron from running crooked or gathering up in the middle of the rollers by attaching it to chains driven by sprocket-wheels which hold the chains apart, all as hereinafter more specifically set forth.

In the drawings, A marks the frame of the machine, in which the operative parts are supported and work.

B is a feed-table, on which the sheets to be fed in are banked. The sheets are fed by hand. The feed-table consists of two parts, one, B, stationary and fixed to the frame, and the other, a front piece, B', attached by hinges *h* to part B, and capable of being raised and lowered by the operation of the toe *e*, Fig. 3, of lever *e*, operated by cam *c* on shaft M of cylinder F. The object of this movement is to deliver the forward edge of the paper to the grippers *g* on cylinder F when the table is raised. Gage-fingers *e*² on the same shaft are lowered by the same movement to allow the sheets to pass in.

The fountain G, which carries the varnish, rests upon the arms I, projecting from the rock-shaft J, to which is also attached the lever K projecting downward and operated by the treadle L. The shaft L' of treadle L is flat on one side and convex on the other, and acts as a cam to give a slight movement to lever K (shown by dotted lines in Fig. 3) to throw the fountain and its varnish-roller into or out of contact with the surface of the main drum F.

The fountain G is provided with a composition varnish-roller, H, turning in the varnish in the reverse direction from the drum F, being geared to it by the long-toothed wheels *v* *w*. A doctor-roll, *w'*, in the fountain (see Figs. 6 and 7) regulates the amount of varnish the roller H is to receive and apply to the paper. This doctor-roll moves slower than the roller H, receiving its motion from it by gear *v w*, Fig. 1, and is adjustable by means of sliding boxes G', Figs. 6 and 7. An agitator or stirrer, *y*, is placed in the fountain to stir the varnish. It is operated by the gears *w w'*, Figs. 6 and 7.

A stationary bar, *x*, Figs. 6 and 7, carrying a series of small rollers, *x'*, is attached outside of the fountain at its inner edge, and serves to prevent the backs of the sheets or boards from dragging on the edge of the fountain when it leaves the feed-board.

The fountain is adjusted in its distance from drum F by means of bolts and set-screws in the grooves of brackets I, Fig. 1.

When the treadle-cam is in the position shown in full lines in Fig. 3, the fountain G is held up and the composition-roller H comes in

contact with the packing on drum F; but when it is desired to mix the varnish, reduce it with oil or spirits, or to run the machine without varnishing, the treadle is reversed to the position shown in dotted lines, and the flat side of the cam brought to the lever, which allows the fountain to fall a short distance, not far enough to throw the long toothed wheels out of gear, but far enough to allow roller H to clear the packing and allow the machine to run idle without damaging the packing. Should the feeder desire to adjust the bank of paper, or should he inadvertently miss feeding a sheet, he can instantly throw down the fountain with 15 out stopping the machine, and raise it again when ready by the operation of the treadle.

The cylinder F has a blanket, F', composed of a pile of thin paper or felt, (see Fig. 5,) which is nailed to the cylinder at one end, and 20 clamped over the edge of the lagging at the other end (where the grippers g' take the paper or card-board) by an iron plate, l', on the bar l, on which is a lever, l', outside the cylinder-head on the gear end, (shown in dotted lines 25 in Fig. 3,) which holds the clamping-plate l' tight when pressed over the rack l', Fig. 3. If the top sheet of this pile-blanket should be soiled by the varnish, it can be cleaned instantly by tearing one sheet off from the pile, 30 when a clean surface is presented to receive the next sheet to be varnished.

Besides the grippers g (which are operated in the same manner as in a cylinder printing-press by means of a tumbler, n, engaging the rollers 35 b b' on the inside of the frame in the usual manner) there is also a series of lifting-fingers, g', on the shaft g', which strip the boards off the packing of the cylinder and lift them onto the fingers a leading to the apron. These fingers 40 g' are operated by a lever, g', on the same shaft, striking a roller, b', on the inside of the frame, Figs. 2 and 3.

The rollers D D', on which the apron runs, are provided with sprocket-wheels on each end, 45 which drive a safety-chain, C', which has lugs or ears l' projecting to one side, to which the canvas of the apron C is riveted to prevent it from shifting on the rollers. (See Fig. 9.)

The roller S is adjustable in the segments Q 50 R (in order to tighten the apron) by means of the sliding journal-boxes B', Figs. 3 and 4.

The machine is driven by a cone-pulley on roller-shaft N, which has also a small gear-wheel, 1, inside of the frame. This wheel gears 55 into a small idler, 2, which runs loose on the shaft a', Fig. 3, which gears into the wheel N

on the shaft M, and drives the cylinder and the varnish-rolls as previously described.

The two sprocket-wheels on the roller D are fast, and the diameter of the roller corresponds 60 with the pitch-line of the sprocket-wheels. All the other sprockets carrying the chain are loose upon their rollers, and free to turn with the chain, regardless of the speed of the roller; hence no adjustment of the relative diameters 65 of the sprocket and roller is necessary in the construction of these wheels. The sprocket-wheels are kept apart the distance required to hold the chain and apron taut sidewise, and prevent sagging or gathering up. 70

The operation has been for the most part suggested in the description of the machine. The sheets are fed face down, by hand, to the cylinder from the front section, B', of the feed-table, which is raised to deliver the sheet to 75 the grippers g. The sheets are then carried over the glossing-roll H, receiving the required coat of varnish; hence, being released by the grippers, they pass over the stripping-fingers to the apron C, by which they are carried down 80 the swinging frame to the off bearers to be borne to the drying apparatus.

Having thus fully described our invention, what we claim, and desire to secure by Letters Patent, is—

1. In a glossing-machine, in combination with the driving and supporting rollers D D' and the swinging frame R, the broad apron C, for delivering the varnished sheets, as described. 85

2. The described device for tripping the fountain, the same consisting of the combination, with the fountain G, of the brackets I I, lever K, and treadle L, all constructed, arranged, and operating substantially as set 90 forth. 95

3. The combination of the sprocket-wheels on shafts D D' D' with the safety-chain and the apron C, in the manner and for the purpose specified. 100

4. The swinging frame R, hung on journals concentric with those of the roller D, which supports and carries the apron C, in the manner and for the purpose stated.

In testimony that we claim the foregoing 105 as our own invention we affix our signatures in presence of two witnesses.

CYRUS CHAMBERS, JR.
